CLAIM

The ornamental design for a light emitting diode, as shown and described.

DESCRIPTION

FIG. 1 is a front top side perspective view of a light emitting diode in accordance with an embodiment of my new design; FIG. 2 is a top plan view of the light emitting diode in accordance with the embodiment of my new design; FIG. 3 is a front elevational view of the light emitting diode in accordance with the embodiment of my new design; FIG. 4 is a rear elevational view of the light emitting diode in accordance with the embodiment of my new design;

FIG. 5 is a left side end elevational view of the light emitting diode in accordance with the embodiment of my new design; and,

FIG. 6 is a right side end elevational view of the light emitting diode in accordance with the embodiment of my new design. The broken line showing of environment (the remaining structure of the light emitting diode) in the Figures is for illustrative purposes only and forms no part of the claimed design.

The opaque line shading illustrates a translucent portion of the light emitting diode.
